PORTABLE BLOWER FOR BARBECUE GRILLS

Arthur Rowley, Green Lake, Wis.

Application June 4, 1956, Serial No. 41,761

Term of patent 14 years

(Cl. D62—2)

FIG. 2

Fig. 1 is a perspective view showing one end and one side of the portable blower for barbecue grills embodying the new design; and

Fig. 2 is a perspective view showing the other end and the other side of the blower.

The dominant features of the design reside in the portions shown in full lines.

I claim:

The ornamental design for a portable blower for barbecue grills, as shown and described.
